Primary Examiner—Philip S. Hyder*Assistant Examiner*—C. Tuttle*Attorney, Agent, or Firm*—Notaro & Michalos**[57]****CLAIM**

The ornamental design for a stabilizing device, as shown and described.

DESCRIPTION

FIG. 1 is a top perspective view of our new design;
 FIG. 2 is a front elevational view thereof; the right side elevational view being a mirror image thereof;
 FIG. 3 is a left side elevational view thereof; the right side elevational view being a mirror image thereof;
 FIG. 4 is a top plan view thereof;
 FIG. 5 is a bottom plan view thereof;
 FIG. 6 is a top perspective view of a second modified embodiment of our design wherein the lower edge is lined for the color red; and,
 FIG. 7 is a left side elevational view thereof the right side elevational view being a mirror image thereof.
 The stabilizing device is shown partially broken away in the various views to indicate indeterminate length.
